UNITED STATES PATENT OFFICE.

LUCIAN L. EBY, OF NORTH FORK, IDAHO.

CRATE.

1,317,438.

Specification of Letters Patent. Patented Sept. 30, 1919.

Application filed March 30, 1916. Serial No. 87,828.

To all whom it may concern:

Be it known that I, LUCIAN L. EBY, a citizen of the United States, residing at North Fork, in the county of Lemhi and State of Idaho, have invented certain new and useful Improvements in Crates, of which the following is a specification.

My invention relates to new and useful improvements in crates and more particularly to a knockdown crate.

The primary object of the invention is the provision of a crate of this character which is simple and inexpensive in construction and which may be easily operated.

A further object of the invention is the provision of means for holding the crate in open position for receiving and holding the articles to be shipped as well as the provision of means for holding the crate in knockdown position.

A still further object of the invention is the provision of a removable top and bottom whereby the sides and ends may be collapsed.

With these and other objects in view the invention consists in the novel details of construction and arrangement of parts which will be more clearly understood from the following description and drawings, in which,

Figure 1 is a view in side elevation, Fig. 2 is top plan view with a section broken away to show the interior,

Fig. 3 is a longitudinal vertical section on the line 3—3 of Fig. 2,

Fig. 4 is a transverse vertical section on the line 4—4 of Fig. 2, and

Fig. 5 is a side view of the crate in knockdown position.

In carrying out my invention I provide sides and ends which are pivotally connected together, the sides comprising a plurality of vertically spaced strips 1 and the ends comprising a plurality of vertically spaced strips 2, the ends of the strips 2 being received between the strips 1 as is clearly illustrated in the drawings. Rods 3 pass vertically through the ends of the strips 1 and 2 whereby the side and end strips are pivotally connected together. Washers 4 are

adapted to be received on the rods 3 against the strips 1, and the ends of the rod are flattened whereby they are held in position.

Staples or eyes 5 are secured to the lowermost strips 1, on the underside thereof, and are used for connecting the bail members to

the crate. These bail members comprise rods 6 which pass through the staples or eyes 5 and beneath the bottom of the crate, right angle extensions 7 which extend vertically of the sides of the crate and cross-rods 8 adapted to extend over the top of the crate and said cross rods 8 are provided intermediate the ends with loops or eyes indicated at 9, and the purpose of which will be presently described. A removable bottom plate 65 indicated at 10 is adapted to be received on the cross-rod 6 between the side strips 1 and a removable top 11 is received on the end strips 2 and between the uppermost side strips 1.

That portion of the rod 6 between the staples or eyes 5 is slightly offset so as to engage the bottom and clamp the same when the bails are swung over in their tying position. This offset portion is clearly illustrated in Fig. 4.

The bails are adapted to be held in raised position by means of cords or wires, indicated at 12, said cords or wires 12 being connected to the eyes 9, as more clearly illustrated in Fig. 2 of the drawings.

The distance between the side extensions 7 of the bail members is preferably greater than the width of the crate, whereby the bails will assume the position indicated in Fig. 5 of the drawings when the crate is in its knockdown position.

Having fully described the details of construction it is thought that the advantages and operation of my crate will be clearly understood. My crate is adapted for shipping vegetables or fruits of various characters and when ready to be filled, the several parts will be in the position illustrated in the drawings with the exception that the cover or top plate 11 will be removed. After the crate is filled the top plate 11 is placed in position and the bails tied in position by means of the cords or wires 12. After the contents of the crate have been removed the top plate 11 and bottom plate 10 are removed and the side and end strips are swung upon the pivot rods 3 to assume the position illustrated in Fig. 5 of the drawings. It will be understood when collapsing the ends and sides it is necessary that the connecting cords or wires 12 be removed from the bails and said bails are swung beyond the ends of the crate. After the sides and ends are collapsed the bails are then swung into the 110

position illustrated in Fig. 5 of the drawings whereby they will extend at an angle across the end and side strips 1 and 2. The cords or wires 12 may then be retied or connected 5 whereby the bails will be held in such position as to retain the crate in its knock-down position. It will be understood that the bottom plate 10 and top plate 11 may be connected to the sides of the crate in any 10 desired manner.

From the above description it will be seen that I have provided a crate which can be held in raised position whereby fruit or vegetables of various characters may be 15 shipped. After the crate is emptied, it may be knocked down, thereby requiring less space for reshipping or returning to the original sender. By such construction and arrangement of parts, my crate may be used 20 a number of times, thereby saving a considerable expense.

If small articles are to be shipped such as small berries, a lining of pasteboard or other suitable material may be inserted between 25 the sides and ends, and across the top and bottom. By this arrangement, the berries will be prevented from falling between the strips 1 and 2. It will be further noted that by having the bail members of greater width 30 than the crate itself, the bails may be folded into the position illustrated in Fig. 5 of the drawings.

Having fully described my invention

Copies of this patent may be obtained for five cents each, by addressing the "Commissioner of Patents, Washington, D. C."

what I claim as new and desire to secure by Letters Patent is:

1. A collapsible crate comprising sides, ends pivotally connected to the sides, a top, a bottom, bails secured to the lower edge of the side members for slidable and longitudinal pivotal movement, said bails being of greater width and height so as to extend beyond and loosely envelop the sides and top of the crate, whereby said bails fold with the crate without being detached therefrom, and means for connecting and drawing the bails into clamping engagement with the top of the crate.

2. A collapsible crate comprising sides, ends pivotally connected to the sides, a top, a bottom, bails secured to the lower edge of the side members for slidable and longitudinal pivotal movement, said bails having an offset portion between the securing means for engaging the bottom and being of greater width and height so as to extend beyond and loosely envelop the sides and top of the crate, and means for connecting and drawing the bails into clamping engagement with the top and bottom.

In testimony whereof I affix my signature 60 in presence of two witnesses.

LUCIAN L. EBY.
